UNITED STATES PATENT OFFICE.

VINCENT G. APPLE, OF DAYTON, OHIO.

DESIGN FOR A DYNAMO-BASE.

45,977.

Specification for Design. Patented June 23, 1914.

Application filed April 17, 1914. Serial No. 832,650. Term of patent 14 years.

To all whom it may concern:

Be it known that I, VINCENT G. APPLE, a citizen of the United States, residing at Dayton, in the county of Montgomery and State of Ohio, have invented a new, original and ornamental Design for a Dynamo-Base, of which the following is a specification, reference being had to the accompanying drawing, forming part thereof.

The figure is a perspective view of a dynamo base, showing my new design.

I claim:

The ornamental design for a dynamo base, as shown.

VINCENT G. APPLE.
